UNITED STATES PATENT OFFICE.

EDWARD LEGER, OF CHICAGO, ILLINOIS.

SHOW-STAND.

SPECIFICATION forming part of Letters Patent No. 271,719, dated February 6, 1883.

Application filed October 21, 1882. (No model.)

To all whom it may concern:

Be it known that I, EDWARD LEGER, of Chicago, in the county of Cook and State of Illinois, have invented certain new and useful Improvements in Show-Stands, of which the following is a full, clear, and exact description, that will enable others to make and use the same, reference being had to the accompanying drawings, and to letters of reference marked thereon, forming a part of this specification.

This invention relates to that class of show-stands that are placed in show-windows for the display of wearing-apparel; and it consists of certain novel features in the construction and arrangement of the parts, as will be hereinafter more fully set forth in detail.

Figure 1 is a front elevation in perspective; Figs. 2, 3, and 4, detached details of construction.

Referring to the drawings, A A' represent the main tubular supporting-standards, provided with an enlarged base for retaining the same in an upright position. The series of sleeves B, inclosing the standards A A', are adapted to have a longitudinal adjustment thereon, and are retained in place by the thumb-screws C. The sleeves B are provided with the socket or tubular part a for the reception of the shank-projection a', formed integral with the part b of the ratchet-clamp. The ratchet-clamp is composed of the two disks b b', having teeth on the inner joining faces, which are adapted to engage with each other. These disks are adjustably secured with relation to each other by means of the thumb-screws a². The part b' of the ratchet-clamp is provided with the lateral projecting arm D. The inner faces of the disks b b' are also recessed for the reception of the coiled spring a³, which encir-

cles the thumb-screws a², and serves to throw the toothed faces of the disks out of engagement with each other, when the thumb-screw is slackened back, which permits the arm or arms D to be adjusted to any desired position. This construction and arrangement forms a strong adjustable joint, enabling the arms D to support a considerable load. The arms D are provided with the sliding socket d, adjustably secured by thumb-screws, and having the enlarged projected part d', which has both sides curved out, as shown in Fig. 4 of the drawings, at e, so as to retain the cross-bars E in position, no matter to what position the arms D are adjusted. If the arms D are turned downward, then the cross-bars are placed so as to bear against the inner side of the curved-out part at e. When the arms are turned upward, then the cross-bars are changed to the opposite side, as fully shown in Fig. 1 of the drawings.

Having thus described my invention, what I claim as new, and desire to secure by Letters Patent, is—

1. The combination, with the standards A A', of the sleeves B, provided with the socket part a, the ratchet-disk b, provided with the shank a', and the disk b', provided with the arm or arms D, substantially as described.
2. The combination, with the arms D, of the adjustable sockets d, provided with the enlarged part d', having both sides curved out at e, and the cross-bars E, substantially as described.

EDWARD LEGER.
